OPERATING MECHANISM FOR INJECTORS

Orla E. Watson, Mission Hills, Kans.

Application June 10, 1957, Serial No. 664,661

3 Claims. (Cl. 74—141.5)

This invention relates to new and useful improvements in operating mechanisms for injectors, and has particular reference to injectors of the type adapted to deliver fluid at very low rates. For example, such an injector is often used to add a demulsifying chemical solution to crude oil as it is pumped from the well, preparatory to cleaning said crude oil of impurities. In such applications, the amount of such chemical solution to be added is very low, amounting often only to 6-8 ounces in 24 hours of continuous operation, or even less. The operating mechanisms used for injectors in such applications have heretofore commonly included reciprocating or oscillating cams driven by a rotating cam actuator driven by some intermittent mechanism such as a ratchet. Difficulties have arisen with this type of mechanism due to the fact that the cam actuator movement is transmitted to the injector substantially as simple harmonic motion, with the result that the operation of the injector is started at a very low speed on each oscillation of the cam. With very low pumping rates, such a slow start of operation often will fail to unseat the check valves forming a part of the injector, due to the fact that all the fluid actually moved at the start of the stroke may be lost through minute leaks in the tubing connections, packing joints and the like of the injector system, with the result that the injector remains effectively inoperative. Such minute leaks are virtually impossible to eliminate completely, and once a leakage path is thus established, it requires an increasingly greater rate of displacement to actuate the injector.

An important object of the present invention is, therefore, the provision in an injector operating mechanism of the class described of a specially formed cam so related to its actuator that each stroke of the injector is initiated at the maximum rate of speed. Such a sudden start will cause immediate unseating of the injector valves and thus start operation of the injector, since the leakage may easily be kept sufficiently small as to be inadequate to pass the fluid displaced by such a sudden commencement of operation. Once the injector valves are positioned properly, continued fluid delivery thereby may be maintained at lower pumping rates.

Another object is the provision of an operating mechanism of the class described wherein the cam is so disposed as to cause a faster operation of the injector during the fluid delivery cycle of the injector than during the fluid intake cycle thereof. Since the fluid must ordinarily be delivered against a much higher pressure than the intake pressure, faster operation during the delivery cycle assists in offsetting any system leakage as described above.

A still further object is the provision, in an operating mechanism of the character described, of a cam which has a substantial period of lost motion with respect to its actuator, whereby said cam may be oscillated manually and rapidly to "prime" the injector by filling all parts thereof with liquid. With injectors of very low capacity, the normal operating rate is usually not sufficient to perform the priming function.

2

Other objects are simplicity and economy of construction, efficiency and dependability of operation, and adaptability for use in a wide variety of applications.

With these objects in view, as well as other objects 5 which will appear in the course of the specification, reference will be had to the drawing, wherein:

Fig. 1 is a vertical sectional view through an injector and operating mechanism therefor embodying the present invention, taken approximately on line I—I of Fig. 2, 10 with parts left in elevation, showing the parts at the completion of the fluid intake stroke in solid lines and at the completion of the fluid delivery stroke in dotted lines, and Fig. 2 is a sectional view taken on line II—II of Fig. 1.

Like reference numerals apply to similar parts throughout both of the views, and the numeral 2 applies generally to an injector pump comprising a body member 4 having a straight-through passage 6 formed therethrough, one end of said passage being connected by a conduit 8 to a tank or other source, not shown, of the liquid to be 15 pumped by the injector, and the other end of said passage being connected by a conduit 10 to the apparatus, not shown, to which the pumped liquid is to be delivered. Carried within the pump body are a pair of check valve balls 12 and 14 which cooperate respectively with valve 20 seats 16 and 18 formed in said body to permit fluid flow through passage 6 in one direction only, as indicated by 25 arrows 20.

A passageway 22 formed in body member 4 intersects passage 6 intermediate valves 12 and 14, and a piston or 30 plunger rod 24 is disposed for longitudinal reciprocal movement in said passageway, leakage around said piston being prevented by a packing 26. It will be apparent that when piston 24 is moved to the right as viewed in the drawing, pressure in passage 6 will be reduced. This 35 seats valve 14 firmly, but unseats valve 12 and draws fluid into passage 6. When piston 24 is moved to the left, valve 12 will be seated, while valve 14 will be unseated and fluid delivered through conduit 10. The injector thus constitutes an ordinary positive displacement 40 pump. The specific structure thereof is not pertinent to the present invention, and the drawing is somewhat schematic with respect thereto.

The operating mechanism forming the subject matter of the present invention is carried in a housing 28 which 45 is formed integrally or directly connected to injector body 4 and which serves as a frame for carrying the operating parts thereof. As shown, said housing comprises a hollow rectilinear box having a removable cover 30, and pump piston 24 extends horizontally into the 50 interior thereof. Carried in the housing is a lever 32, said lever having a tubular hub 34 pivoted on an axle 36 disposed in the lower portion of the housing. Said axle is journaled in a pair of bearing blocks 38 affixed respectively to opposite side walls of the housing by screws 40, 55 and is disposed transversely to and downwardly offset from piston 24. Adjacent the upper end of the lever, a link 42 is pivoted thereto at 44, the opposite end of said link being pivoted at 46 to the inner end of piston 24, whereby oscillation of said lever will cause a corresponding 60 reciprocation of the piston. Since the lever obviously need not be attached directly to the piston, and said connection could be through any suitable intervening means such as might be indicated by convenience or accessibility requirements, the piston 24 may be termed simply an 65 "operating member" for the injector pump.

Carried in housing 28 is a shaft 48 which is parallel 70 to axle 36 and disposed adjacent the free end of lever 32, said axle being journaled at one end in a bearing block 50 attached to a side wall of the housing, and extending through a stuffing box 52 provided in the opposite wall of the housing to a point external to the

housing. A lever 54 is affixed to the external end of the shaft. Mounted on the shaft within the housing is a toothed ratchet wheel 56, said wheel having a tubular hub 58 which rotates freely on the shaft. Fixed rigidly on shaft 48 adjacent the ratchet wheel, and extending radially, is an arm 60. Pivoted to the outer end of said arm, on a pivot pin 62 parallel to shaft 48, is a pawl 64. As best shown in Fig. 1, said pawl is provided with a tooth 66 which engages the toothed periphery of wheel 56, and with an enlarged counterweight 68 which urges said tooth into engagement with the wheel. Thus when lever 54 is oscillated by any suitable means, shaft 48 and arm 60 will be correspondingly oscillated. During clockwise movement of said arm, as viewed in Fig. 1, pawl tooth 66 will turn ratchet wheel 56 in the direction indicated by arrow 70. During counterclockwise movement of arm 60, the tooth moves inoperatively over the ratchet teeth. In order to prevent wheel 56 from turning in a reverse direction while pawl tooth 66 is inoperative, a holding dog 72 is pivoted at 74 to a lug 76 formed integrally with the housing, said dog having a tooth 78 which engages the ratchet teeth by gravity.

Affixed in wheel 56, eccentrically to the axis thereof, is an axle 80 on which is mounted a ball-bearing roller 82; said roller lying substantially in the plane of movement of lever 32. Said roller serves as an actuating member for a cam 84 which comprises a substantially hook-shaped extension of lever 32 lying in the plane of movement of the lever. Said cam extension substantially embraces shaft 48 and is operably engaged by roller 82. It will be seen that the cam presents a pair of confronting lobes 86 and 88 (Fig. 1), lobe 86 being disposed at the upper end of lever 32 proper and positioned to pass beneath shaft 48, and lobe 88 being disposed at the extreme end of the hook-shaped extension 84 and positioned to pass above shaft 48 as the lever is oscillated.

The operation of the device is believed to be readily apparent. Lever 54 may be oscillated by any suitable means. In the case of the oil well application previously discussed, lever 54 may be linked directly to the oscillating beam of the main well pump so as to be operated thereby. As it oscillates, it functions through arm 60 and pawl tooth 66 to turn ratchet wheel 56 intermittently in a clockwise direction, as previously described. As said wheel turns from the solid line position in Fig. 1, roller 82 will engage cam lobe 86 and pivot lever 32 to the position shown in dotted lines, thereby moving piston 24 through its fluid delivery stroke. As rotation of the ratchet wheel continues, the roller will engage cam lobe 88 and pivot the lever back to the solid line position, moving piston 24 through its fluid intake stroke. The roller does not contact any portion of cam 84 except lobes 86 and 88.

It will be seen that since lobes 86 and 88 are spaced apart a distance greater than the diameter of roller 82, the roller will necessarily engage the cam lobes during only portions of the orbital movement of the roller. Generally, the operative sectors of the rotation of the roller are so disposed that the component of its movement in a direction at right angles to lever 32 is as great as possible, so that the speed of movement of the lever, and hence of the injector piston, is as rapid as possible commensurate with the speed of the ratchet wheel. As previously discussed, as rapid piston movement as possible is effective in preventing failure of the injector valves 12 and 14 due to minute leakages of fluid. More specifically, it will be seen that as the roller engages each of the cam lobes, the roller is moving substantially at right angles to the lever, which provides that the pumping stroke will have the greatest possible initial speed. As previously explained, a high starting speed is particularly effective in causing valves 12 and 14 to open efficiently, while the stroke may be completed at a relatively low speed.

Also, it will be noted that operation of roller 82 on cam lobe 86 moves piston 24 in its fluid delivery stroke, and that said lobe is closer to the pivot 36 of lever 32 than lobe 88, which operates to cause the fluid intake stroke. Thus the fluid delivery stroke is accomplished at a much greater speed than the intake stroke. Since the fluid delivery is ordinarily accomplished at a much higher pressure than the intake, this feature provides further insurance that the injector will function efficiently and will not fail at very low capacities due to fluid leakage.

It will be seen also that with roller 82 advanced slightly from the solid line position of Fig. 1, lever 32 can be oscillated freely by hand without interference from the roller, simply by grasping the cam extension 84. Thus the injector can be operated very rapidly to prime it at the beginning of a period of operation. This is considered a valuable feature of convenience. Access for manually turning the ratchet wheel and oscillating the lever 20 may be had by removing cover 30. The housing would ordinarily be partially filled with oil to lubricate the operating parts.

While I have shown and described a specific embodiment of my invention, it will be apparent that many minor changes of structure and operation could be made without departing from the spirit of the invention as defined by the scope of the appended claims.

What I claim as new and desire to protect by Letters Patent is:

30. 1. For use in conjunction with an injector pump operable by reciprocal movement of an operating member, movement of said member in one direction causing fluid intake by said pump and movement of said member in the opposite direction causing fluid delivery by said 35 pump, an operating mechanism comprising a frame, a lever pivoted in said frame on an axis transverse to the direction of movement of said operating member, means interconnecting said operating member to said lever at a point spaced apart from the axis of the lever, whereby 40 oscillation of said lever will cause reciprocal movement of said operating member, a cam follower carried by said lever and including a pair of confronting lobes spaced apart angularly of said lever, a cam member carried for orbital rotation by said frame on an axis 45 parallel to the axis of said lever and disposed intermediate said follower lobes, the angular spacing between said lobes being less than the diameter of the orbit of said cam member, whereby rotation of the latter will cause oscillation of said lever, the spacing between said 50 follower lobes being substantially greater than the maximum dimension of said cam member in the plane of said lobes, whereby said cam member will have periods of lost motion with respect to said follower during each rotation of said cam member and whereby said lever 55 may be oscillated manually to prime the pump at certain angular positions of said cam member, and means operable to rotate said cam member.

2. An injector operating mechanism as recited in claim 1 wherein said lobes are so positioned that they are 60 engaged respectively by said cam member as said cam member is moving approximately at right angles to said lever, whereby the strokes of said follower member are initiated at the greatest possible velocity.

65. 3. An injector operating mechanism as recited in claim 1 wherein said lobes are disposed at respectively greater and smaller distances from the lever axis, action of said cam member on the lobe closer to said lever axis being operable to move said operating member in its fluid delivery stroke, and wherein said lobes are so positioned 70 as to be engaged respectively by said cam member as the latter is moving approximately at right angles to said lever.
